UNITED STATES PATENT OFFICE.

GEORGE E. CURTISS, OF NEW BRITAIN, CONNECTICUT.

DESIGN FOR A GLASS-HOLDER.

44,301.

Specification for Design.

Patented July 8, 1913.

Application filed April 21, 1913. Serial No. 762,739. Term of patent 7 years.

To all whom it may concern:

Be it known that I, GEORGE E. CURTISS, a citizen of the United States, and a resident of New Britain, in the county of Hartford, State of Connecticut, have invented a new, original, and ornamental Design for a Glass-Holder, of which the following is a specification, reference being had to the accompanying drawings, forming part hereof.

The figure is a side elevation of the structure embodying my invention.

I claim:

The ornamental design for glass holder as shown.

GEORGE E. CURTISS.

Witnesses:

HENRY FAGAN,
JOS. F. LAMB.
